TURBINE BLEEDER-VALVE.

1,308,407.

Specification of Letters Patent.

Patented July 1, 1919.

Application filed June 16, 1916. Serial No. 103,946.

To all whom it may concern:

Be it known that we, BENJAMIN G. FERNALD and JAMES L. MOORE, of New York, in the county of New York, and in the State 5 of New York, and Wellsville, county of Allegany, and State of New York, respectively, have invented a certain new and useful Improvement in Turbine Bleeder Valves, and do hereby declare that the following is a full, clear, and exact description thereof.

Our invention relates particularly to bleeder valves applied to turbines, and especially steam turbines.

15 Hitherto bleeder valves, as applied to turbines, have been arranged with automatic means for varying the amount of steam passing through the same by providing nozzle control in the turbine, that is to say 20 by providing means for cutting off the supply of steam from one or more of the nozzles at a given point in the turbine, or they have been arranged with an automatic throttle valve or back pressure valve requiring the 25 steam which flows to the condenser to pass outside of the turbine casing and back again into the interior of the same. The bleeder valves providing nozzle control have necessitated the use of an annular valve ring 30 on one of the diaphragms or turbine sections, so as to successively cut off the supply of steam from the nozzles at that stage in the turbine. The presence of such a valve ring, however, extending entirely around the circumference of the turbine, prevented the 35 turbine from being entirely uncovered and exposed to view for inspection and repairs by lifting the upper half of the turbine casting with the attached diaphragms and other 40 parts attached thereto. The bleeder valves of the throttle type, or back pressure type, furthermore, required the passage of the steam outside of the turbine casing and back into the same, which rendered the construction complex and generally inefficient.

An object of our invention is to provide a bleeder valve which may be of the throttle type, but which is located in the interior of the turbine so as to obviate the necessity of 50 passing the steam outside of the turbine casting and back into the same. A further object is to provide a bleeder valve in the form

of a special section or diaphragm which may be substituted in the turbine for any one of the diaphragms contained within the 55 same without requiring extensive changes in the construction of the turbine in which it is introduced, that is to say, without further change than perhaps the lengthening of the shaft and the casing. A further object is 60 to provide such a valve which will permit the turbine to be opened to view for inspection and repairs merely by lifting the upper half of the same, and the upper halves of the 65 diaphragms which are attached thereto without in any way disturbing the parts of the bleeder valve. A still further object is to provide a bleeder valve, which may be operated by hand if so desired. A further object is to provide a gridiron valve for this 70 purpose, and a means for operating the same which will give an accurate adjustment of the steam pressure in the heating system supplied by the steam coming from the section containing the bleeder valve.

75 A further object of our invention is to provide the bleeder valve outlet with a check valve which will normally operate to prevent the passage of steam from the system supplied by the bleeder valve back into the 80 turbine and thus cause over-speeding. A further object is to provide a valve in the bleeder outlet which will be positively closed by an emergency governor when there is any over-speeding caused by the passage of 85 steam back into the turbine from the system supplied by the bleeder valve, the same acting so as to prevent such reverse movement of the steam even in the case where the check valve for any reason becomes inoperative. A further object of our invention is to provide valves of the above character 90 which are operated in connection with an automatically closing throttle valve adapted to be brought into operation by the emergency governor in case of over-speeding.

95 While our invention is capable of embodiment in many different forms for the purpose of illustration we shall show only one form thereof in the accompanying drawings, in which,

100 Figure 1 is a longitudinal vertical section of a turbine carrying a bleeder valve section made in accordance with our invention;

Fig. 2 is a transverse vertical section of the same showing the bleeder valve section in place;

Fig. 3 is a longitudinal vertical section of the bleeder valve section;

Fig. 4 is a section of a detail enlarged;

Fig. 5 is a horizontal section of a bleeder valve section as shown in Fig. 3;

Fig. 6 is a vertical section showing a speed 10 governor and an emergency governor;

Fig. 7 is a horizontal section showing details of the emergency governor, and

Fig. 8 is a sectional view of the turbine casing and bleeder outlet, showing the 15 bleeder outlet valve.

In the drawings we have shown a steam turbine having an inlet 1 for steam, and an outlet 2 for the exhaust steam, a base frame 2^a, an oil supply tank 2^b therein, an oil pump 2^c, and having an outer casing comprised of semi-circular heads 3, 3^a, 4, 4^a, and lagging 4^b and 4^c. Through the turbine casing there extends a shaft 5, carrying disks 5^a, having on their periphery blades 6. The blades 6, and the parts, in general, of the turbine, may be of any suitable type, but by way of example they may be of the multi-pressure stage "impulse" type. Between the disks 5^a there are located partitions or diaphragms 30 comprising lower halves 7 attached to the lower part of the casing 3, and upper halves 8 attached to the upper half of the casing 4. These diaphragms are provided with nozzles 9 to direct the steam against the blades 6. 35 As shown in Fig. 1, at any suitable point in the turbine, there may be introduced one of our special bleeder valve diaphragms comprising a lower half 10 and an upper half 11. The upper half 11 of this diaphragm 40 is preferably not provided with nozzles, but the lower half 10 is provided with nozzles 12 (Fig. 3), which discharge the steam from a chamber 13 formed by the face of the diaphragm section 10, and a partition 14 in the 45 rear thereof. This partition 14 has attached to its rear face, a pair of guides 15 by means of screws 16 for guiding a gridiron valve 17. The gridiron valve 17 has attached to one end thereof a piston rod 18 which is connected to a piston 19 operating in a cylinder 20 supported upon a casting 21 attached to the bleeder valve diaphragm section 10 in any suitable manner. The piston 20 is operated by oil, which may be admitted to or 50 discharged from one end or the other of the cylinder by means of passageways 22 and 23 (Fig. 4). The passageway 22 communicates with a port 24 in a valve casing 25 attached to one side of the cylinder 20, and 55 the passageway 23 communicates with a port 26 also in the valve casing 25. Oil under pressure is supplied to the valve casing 25, by means of a pipe 27 and discharged from the same by means of a pipe 28. The flow 60 of the oil to and from the ends of the cyl-

inder 20 is controlled by the position of a plunger valve 29, one end of which is connected to a lever 30 pivotally supported in any suitable way from the casting 21. Intermediate its ends, the lever 30 is pivotally connected to a rod 31 which is connected to a diaphragm 32 located in a diaphragm casing 33 supported in any suitable way upon the cylinder 20. A spring 34 surrounds the rod 31 and is interposed between the diaphragm 32 and a stationary sleeve 35 secured to the cylinder 20 through which the rod 31 passes. In the outer face of the diaphragm casing 33 there is a steam inlet 36, which is connected by a pipe 37 to the heating system to which the steam is supplied from the bleeder valve section so that one side of diaphragm 32 is subjected to heating system pressure. The steam which is supplied to the heating system passes out of the 85 bleeder valve section by means of a pipe 38 which may be connected in any suitable way to said heating system. It will be understood that the pipe 38 is located in the bleeder valve section at the rear of the partition 14. Pivot to the piston rod 18 there is also provided a hand lever 39 which is pivotally and slidably supported intermediate its ends upon the casting 21. On the main shaft 5 of the turbine there is a worm 40 (Fig. 6), which drives a worm wheel 41 on a vertical governor shaft 42. This shaft 42 is provided with bearings in, and passes upwardly through a governor casing 43, and intermediate its ends is provided with a ball 90 governor 44, which, by centrifugal action is adapted to force upwardly a sleeve 45 on the shaft 42, which sleeve operates upon a spring 46 resting at its upper end against the under face of a sleeve 47 which operates 100 against a carriage 48 to which a lever 49 is pivoted. The lever 49 is provided with a link 50, the lower end of which rests against the lower end of a spring 51 in a housing 52 carrying said spring, said housing being connected by a screw-threaded rod 53 to a bracket 54 on the casing 43. Hand wheels 55 and 56 are provided on the screw 53 above and below the bracket 54. These parts attached to the end of the lever 49 comprise a 110 synchronizer which is adapted to be used in connection with turbines driving alternators, the hand wheels 55 and 56 providing a means for adjusting the tension of the spring 51, and, therefore, adjusting the normal speed 115 of the turbine. Near the middle of the lever 49 there is, furthermore, provided a link 57 which is connected to a pilot valve 58 having annular recesses 59 and 60, co-operating with inlet ports 61 and 62 in an oil supply pipe 120 63 provided with oil under pressure by any suitable means. Said pilot valve 58 has, furthermore, an annular recess 64 which co-operates with an exhaust outlet 65 for the 125 exhaust oil. Oil supplied in this manner is 130

discharged through outlet 65 and admitted to one or the other of two pipes 66 and 67 which lead respectively to the upper and lower ends of a cylinder 68 provided with 5 a relay piston 69, which is attached to a throttle valve rod 70, having a throttle valve 71 located in a steam supply pipe 1. In order to adjust the range of variations in speed, the end of the lever 49 is connected 10 by a screw-threaded rod 72 to a lever 73 pivotally supported upon the steam pipe 1, and having its other end connected to the throttle valve rod 70. The lever 73 carries a plurality of holes 74 by the adjustment of the 15 rod 72 in which the range of speeds is varied.

An emergency governing means is also provided. For this purpose the governor shaft 42 has located around the same an eccentrically situated weight 75 (Fig. 7), said 20 weight having a pin 76 fitting in a recess 77 in a collar 78 secured on said shaft 42, and a spring 79 diametrically opposite to the pin 76 and fitting in a recess 80 in said collar 78. The weight 75 is rotated by a plurality of 25 pins 82 (Fig. 6), projecting into recesses 83 in a plate 84 secured on the shaft 42, said plate being furthermore provided with rollers 85 for supporting said weight 75. Said plate 84 is furthermore provided with a plurality of bolts 86 (Fig. 7) which extend upwardly through the weight 75 and prevent 30 its movement in a vertical direction. When the speed of the turbine becomes very excessive, the weight 75 is thrown outwardly by 35 centrifugal force until it contacts with a block 87 located in the casing 43. The block 87 moves upwardly in opposition to a spring 88 in the casing 43, thereby moving in the same direction a rod 89, which is attached to 40 a trip-lever 90 having a pivot 91 on a bracket 92, extending from the side of the casing 43. When the lever 90 has been moved in this manner, its inner end moves away from its 45 normal position over a valve 93, located in a valve chamber 94 connected to a steam supply pipe 95, thus permitting the passage of steam from said pipe 95 into a pipe 96 connected with the valve chamber 94, said steam passing thence into two branch pipes 97 and 50 98, which lead respectively to a combined check and trip-valve in the bleeder outlet and a similar valve in the steam supply pipe 1. The valve 93 can be reset by a hand lever 93^a pivoted to the bracket 92, and having a 55 spring 93^b, which normally holds the lever 93^a out of contact with the valve 93. The pipe 97 leads to the lower end of a cylinder 98^a (Fig. 8), the upper end of which is provided with a port 99, and a by-pass 100 for 60 cushioning. In the interior of the cylinder there is a piston 101 located on a rod 102 having a yoke 103, adapted to slide over a valve rod 104 extending downwardly into a valve casing 105, and having a check valve 65 106 therein, said valve casing 105 being at-

tached to the bleeder valve outlet pipe 38. At its upper end the valve rod 104 is connected with a lever 106^a having a weight 107 on its outer end which normally retains the check valve 106 in closed position. In 70 case of an emergency, as for example, when the valve 106 has become stuck, the emergency governor will operate to draw the yoke 103 upwardly, thereby closing the check valve 106. The pipe 98, furthermore, 75 leads to an automatic trip-valve 108 in the steam supply pipe, which is constructed in the same manner as the valve to which the pipe 97 leads, except instead of the weighted lever 106, there is a hand wheel 109 which 80 normally allows the valve 108 to be in open position, but permits it to be closed by hand when desired, and to be closed, furthermore, by steam pressure in case the speed of the turbine becomes very excessive. 85

In the operation of our invention, steam will be supplied to the turbine through the passageway 1 and will impinge on the blades 6 from the nozzles 9, so as to rotate the disks 5^a and drive the shaft 5. In its passage 90 through the turbine the steam will, at the point where the bleeder valve diaphragm is located, pass partly out of the same through the outlet pipe 38 from which it may lead to any desired point as, for example, a heating 95 system for a building or a heating apparatus in some manufacturing process. In the operation of the bleeder valve 17 the steam under pressure in the heating system is conveyed by the pipe 37 to the diaphragm 32, 100 which, according to its position as determined by the spring and steam pressure, determines the position of the valve 29 and, therefore, the inlet or outlet of steam to or from one or the other of the ends of the 105 cylinder 20, so as to move the piston 19, and as a consequence the gridiron valve 17. It will be seen that the bleeder valve section 10, 11, may be introduced at any desired point in a turbine in substitution for one of the 110 partitions 7, without requiring extensive changes in the parts. If at any time it should be found necessary to inspect the interior of the turbine, this may readily be done by lifting up the upper half of the turbine casing 4, together with the upper halves of the diaphragms 8, without in any way disturbing the position of the gridiron valve 17, and the operating parts for the same attached thereto. This uncovers the disks 5^a 115 with their attached blades 6, as well as the shaft 5, so as to enable the same to be readily repaired. The speed of the turbine is normally controlled by the ball governor 44. As the balls of the governor move outwardly 120 while the speed is increasing the sleeve 45 is moved upwardly thereby moving the lever 49 and shifting the pilot valve 58 so as to admit oil through the pipe 67 to the lower end of the cylinder 68, thereby elevating the 125 130

piston 69 and closing to some extent the throttle valve 71. This movement draws the rod 72 downwardly, thereby depressing the rod 49 and again moving the pilot valve 58 toward its closed position, thus restoring the turbine to its normal speed. The range of movement in such speed variations is controlled by the position of the rod 72 in the holes 74, located in the lever 73. The normal speed of the turbine is adjusted by the hand wheels 55 and 56, the said hand wheel 56 being provided for the purpose of depressing or elevating the end of the lever 49 to which it is attached. When the speed of the turbine becomes very excessive, the weight 75 is thrown outwardly by centrifugal force, thereby moving the lever 90 and releasing the valve 93. The steam then passes from the pipe 95 into the pipes 97 and 98, so as to operate upon the piston 101 on the bleeder check and automatic trip valve, thereby drawing the check valve 106 upwardly and closing the same, and thus preventing steam in the heating system from passing into the turbine. At the same time said steam also acts on the valve 108, and in a similar way closes said valve which is located in the steam pipe 1. It will, of course, be understood, however, that the bleeder check valve 106 and the automatic trip valve 108, instead of being actuated by steam pressure may be actuated by a supply of oil under pressure or by means of any other fluid medium. The movements of these valves 106 and 108 are cushioned when closing at the upper ends of their strokes. Over-speeding sometimes occurs from the sticking of the check valve 106, and it is for this reason that the automatic trip adjustment for positively closing said valve is provided. In a similar way over-speeding sometimes occurs from the sticking of the throttle valve 71, and it is for this reason that the automatic trip valve 108 is provided in the steam inlet pipe. Furthermore, both of these valves 106 and 108 are so arranged that they can be closed by hand, as for example, by movement of the levers 106 and 109.

While we have described our invention above in detail, we wish it to be understood that many changes may be made therein without departing from the spirit of our invention.

We claim:—

1. A turbine casing having a detachable section, a diaphragm therein having a similar detachable section and a bleeder valve of the throttle type carried entirely by the remaining portion of said diaphragm.
2. A turbine casing having a detachable section, a diaphragm therein comprising a plurality of sections detachably secured together, and a bleeder valve carried entirely by one of the diaphragm sections.

3. A turbine casing having a detachable section, a diaphragm therein comprising a plurality of sections detachably secured together, and a bleeder valve entirely carried by the lowermost section of said diaphragm. 70
4. A turbine having a casing, comprised of centrally separable sections, and a diaphragm comprising centrally separable sections having the upper half closed and on its lowermost section a bleeder valve of the throttle type in the interior of said casing. 75
5. A turbine having a casing, comprised of centrally separable sections, and a diaphragm comprising centrally separable sections, having the upper half closed and on its lowermost section a bleeder valve of the gridiron type in the interior of said casing. 80
6. A turbine having a casing, comprised of centrally separable sections, and a diaphragm comprising centrally separable sections having on its lowermost section a bleeder valve of the throttle type in the interior of said casing, the lower half of the bleeder valve diaphragm having nozzles, and a chamber connecting the same to the bleeder valve. 85 90
7. A turbine having a casing, comprised of centrally separable sections, and a diaphragm comprising centrally separable sections having on its lowermost section a bleeder valve of the gridiron type in the interior of said casing, the lower half of the bleeder valve diaphragm having nozzles, and a chamber connecting the same to the bleeder valve. 95 100
8. A turbine having a casing, comprised of centrally separable sections, and a diaphragm comprising centrally separable sections having the upper half closed and on its lowermost section a bleeder valve of the throttle type in the interior of said casing, the lower half of the bleeder valve diaphragm having nozzles, and a chamber connecting the same to the bleeder valve. 105 110
9. A turbine having a casing, comprised of centrally separable sections, and a diaphragm comprising centrally separable sections having the upper half closed and on its lowermost section a bleeder valve of the gridiron type in the interior of said casing, the lower half of the bleeder valve diaphragm having nozzles, and a chamber connecting the same to the bleeder valve. 115 120
10. In a turbine, a diaphragm made up of sections detachably secured together, one of said sections provided with means to support a bleeder valve and with ports adapted to coöperate with such valve. 125
11. In a turbine, a diaphragm made up of sections detachably secured together, one of said sections having a valve seat adapted to coöperate with a bleeder valve, a chamber adjacent such valve seat, and nozzles leading from such chamber.
12. In a turbine, a diaphragm made up of 130

- sections separable on the horizontal line, the lower of said sections being provided with means to support a bleeder valve, and nozzles adapted to be throttled by such valve.
- 5 13. A turbine having a bleeder section and an automatic trip valve adapted to normally act as a check valve located in the outlet from the same.
14. A turbine having a bleeder section and 10 an automatic trip valve adapted to normally act as a check valve located in the outlet from the same, and an emergency governor controlling the same.
15. A turbine having a bleeder section and 15 an automatic trip valve adapted to normally act as a check valve, and having a weighted closing lever located in the outlet from the same.
16. A turbine having a bleeder section and 20 an automatic trip valve adapted to normally act as a check valve, and having a weighted closing lever located in the outlet from the same, and an emergency governor controlling the same.
- 25 17. A turbine having a bleeder section and an automatic trip valve adapted to normally act as a check valve, and having a weighted closing lever located in the outlet from the same, comprising means for closing said 30 valve when the turbine exceeds its normal range of speeds.
18. A turbine having a bleeder section and an automatic trip valve adapted to normally act as a check valve located in the outlet 35 from the same, an automatic trip valve in the steam supply pipe for the turbine, and an emergency governor controlling said valves.
19. A turbine having a bleeder section and 40 an automatic trip valve adapted to normally act as a check valve located in the outlet from the same, an automatic trip valve in the steam supply pipe for the turbine, and an emergency governor controlling said 45 valves, comprising means for closing said valves when the turbine exceeds its normal range of speeds.
20. A turbine having a bleeder section and an automatic trip valve adapted to normally 50 act as a check valve, having a weighted closing lever located in the outlet from the same, an automatic trip valve in the steam supply pipe for the turbine, and a governor controlling said valve.
- 55 21. A turbine having a bleeder section and an automatic trip valve adapted to normally act as a check valve located in the outlet from the same, an automatic trip valve in the steam supply pipe, and adapted to be operated by hand when desired, for the turbine, and a governor controlling said valves.
22. A turbine having a bleeder section and an automatic trip valve adapted to normally 60 act as a check valve, having a weighted closing lever located in the outlet from the same, an automatic trip valve in the steam supply pipe for the turbine, and a governor controlling said valves.
- same, an automatic trip valve in the steam supply pipe, and adapted to be operated by hand when desired, for the turbine, and a governor controlling said valves.
23. A turbine comprising a casing having 70 a removable section, a diaphragm having a removable section, and a bleeder valve located in the fixed portion of the diaphragm.
24. A turbine comprising a casing and a diaphragm therein, said parts having sections detachable to expose the interior of the turbine, and a gridiron valve supported in a complementary part of the turbine remaining when said detachable sections are removed.
25. In a turbine, a sectional casing, a sectional diaphragm in said casing, and a bleeder valve movable transversely of the diaphragm.
26. In a turbine, a sectional casing, a sectional diaphragm in said casing, and a gridiron valve movable transversely of the diaphragm.
27. In a turbine, a sectional diaphragm, and a bodily movable bleeder valve located 90 within the lower portion of the diaphragm and movable transversely thereof.
28. A turbine having a bleeder section, a positively actuated automatic trip valve adapted to normally act as a check valve located in the outlet from the same, and means for regulating the pressure in said outlet.
29. A turbine having a bleeder section, an automatic trip valve adapted to normally act as a check valve located in the outlet 100 from the same, an emergency governor controlling said valve, and means for regulating the pressure in said outlet.
30. A turbine having a bleeder section, a positively actuated automatic trip valve 105 adapted to normally act as a check valve and having a weighted closing lever located in the outlet from the same, and means for regulating the pressure in said outlet.
31. A turbine having a bleeder section, an automatic trip valve adapted to normally 110 act as a check valve and having a weighted closing lever located in the outlet from the same, an emergency governor controlling said valve, and means for regulating the pressure in said outlet.
32. A turbine having a bleeder section, an automatic trip valve adapted to normally act as a check valve located in the outlet from the same, means for regulating the 115 pressure in said outlet, an automatic trip valve in the steam supply pipe for the turbine, and an emergency governor controlling said valves.
33. A turbine having a bleeder section, an automatic trip valve adapted to normally 120 act as a check valve located in the outlet from the same, means for regulating the pressure in said outlet, an automatic trip valve in the steam supply pipe for the turbine, and an emergency governor controlling said valves.
34. A turbine having a bleeder section, an automatic trip valve adapted to normally 125 act as a check valve located in the outlet from the same, means for regulating the pressure in said outlet, an automatic trip valve in the steam pipe for the turbine, and

- an emergency governor controlling said valve, comprising means for closing said valve when the turbine exceeds its normal range of speed.
5. 34. A turbine having a bleeder section, an automatic trip valve adapted to normally act as a check valve located in the outlet from the same, means for regulating the pressure in said outlet, an automatic trip valve in the steam supply pipe adapted to be operated by hand when desired, and an emergency governor controlling said valves.
- 10 35. A turbine having a bleeder section, an automatic trip valve adapted to normally act as a check valve and having a weighted closing lever, located in the outlet from the same, means for regulating the pressure in said outlet, an automatic trip valve in the steam supply pipe adapted to be operated by hand when desired, and an emergency governor controlling said valves.
- 15 36. A turbine having a bleeder section, an automatic trip valve located in the outlet from the same, a governor for the turbine, and positive means controlled by said governor for forcing said valve against its seat when the turbine exceeds its normal range of speed.
- 20 37. A turbine comprising a casing and a diaphragm contained therein, said parts having sections detachable to expose the interior of the turbine, and a bleeder valve supported in a complementary part of the turbine remaining when said detachable sections are removed.
- 25 30 35

In testimony that we claim the foregoing we have hereunto set our hands.
